(57) **CLAIM**

The ornamental design for an inter-connectable module for man-made lawn, as shown and described.

DESCRIPTION

FIG. 1 is a perspective view of an inter-connectable module for man-made lawn showing my new design

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of the inter-connectable module for man-made lawn shown in use connected to additional modules.

The broken lines in the drawings represent additional unclaimed inter-connectable modules.
